BOTTLE

Irvin R. Linnard, Montclair, N. J.

Application September 13, 1950, Serial No. 12,175

Term of patent 14 years

(Cl. D58—6)

To all whom it may concern:

Be it known that I, Irvin R. Linnard, a citizen of the United States of America, residing at Montclair, in the county of Essex, State of New Jersey, have invented a new, original, and ornamental Design for a Bottle, of which the following is a specification, reference being had to the accompanying drawing, forming part hereof.

In the drawing, Fig. 1 is a front elevational view of a bottle, showing my new design; Fig. 2 is a side elevational view; and Fig. 3 is a top plan view.

I claim:

The ornamental design for a bottle, as shown.

IRVIN R. LINNARD.
